W. A. Sauer.

UNITED STATES PATENT OFFICE.

JOHN J. O'CONNOR, OF DAYTON, OHIO, ASSIGNOR TO THE SHOTT MANUFACTURING COMPANY, OF CINCINNATI, OHIO, A CORPORATION OF OHIO.

COUCH-HAMMOCK STAND.

Application filed March 15, 1923. Serial No. 625,187.

To all whom it may concern:

Be it known that I, JOHN J. O'CONNOR, a citizen of the United States, residing at Dayton, in the county of Montgomery and 5 State of Ohio, have invented certain new and useful Improvements in Couch-Ham- mock Stands, of which the following is a specification.

My invention pertains to frames or sup- 10 ports, more particularly those adapted to sustain hammocks, especially those of the couch style.

One object of the invention is to provide a structure of this character which possesses 15 adequate strength and which may be folded into small compass for shipment or stor- age.

A further aim of the invention is to sup- 20 ply a construction of this type which not only does not present manufacturing diffi- culties but which may be made economically, the structure being such that it is unlikely to become damaged or injured in service or during transportation.

25 To enable those skilled in this art to have a full and complete understanding of the present invention and its several structural and functional advantages, in the accom- panying drawing forming a part of this 30 specification and throughout the several views of which like reference characters refer to the same parts, I have illustrated a de- sirable and at present preferred embodiment of the invention.

35 In this drawing:

Figure 1 is an elevation of the novel struc- ture, the legs being broken away in part;

Figure 2 is an end elevation of the con- struction shown in Figure 1;

40 Figure 3 is a vertical cross-section through the main or top bar of the frame adjacent to one of its ends;

Figure 4 is a fragmentary central vertical section;

45 Figure 5 is a vertical section on line 5—5 of Figure 1 on an enlarged scale;

Figure 6 is a vertical section on line 6—6 of Figure 1 on an enlarged scale;

Figures 7 and 8 show the construction at 50 the lower ends of the supporting legs;

Figure 9 shows in elevation the frame as folded for shipment or storage; and

Figure 10 is a cross-section on an enlarged scale through the folded structure.

55 Referring to the drawings, it will be per-

ceived that the frame comprises a main top angle-bar 21 preferably slightly upwardly bowed or arched and disposed with its edge upward, its two flanges at right angles to one another sloping in opposite 60 directions from such edge at an inclination of forty-five degrees.

At each end such bar has a bracket 22 riveted against the under faces of its pair of flanges at 23, 23, the downwardly project- 65 ing ears of such bracket being bent inwardly somewhat toward one another so that they present an acute angle to one another whereby the spread of the supporting legs will not be excessive.

70 These two legs 24 and 25 at each end of the frame are pivoted at 26 and 27 respec- tively to the ears of the bracket 22 thus permitting the legs to assume operative po- sitions as shown in Figures 1, 2, 3 and 4 or 75 to be folded up against the main bar 21 as indicated in Figures 9 and 10.

76 At its lower end or elsewhere along its length, each leg 24 has a base or leg stiffening bar 28 pivoted or hinged thereto at one 80 end at 29, the opposite end of the bar having a headed stud or pin 31 designed to be received in the socket or slot 32 cut in the lower end of the companion leg 25, whereby by the element 28 holds the two legs prop- 85 erly spaced apart.

86 At the points 33, the opposite flanges of the angle bar 21 are inwardly deflected or squeezed to bring such parts practically par- 90 allel to the depending ears of the brackets 22 and a collapsible brace 35, 37 is pivoted at 34 to each part 33 and at 38 to the flange of the corresponding leg, the two elements 35 and 37 being hinged together at 36, the part 35 having a recess 39 designed to ac- 95 commodate the pin 41 on the other part 37 to prevent them from passing beyond center.

96 On two curved pins or rivets 42 extended through holes in the pair of flanges of the 100 angle bar 21 the couch hammock support- ing hooks 43 are mounted for rocking or oscillation.

When the frame is unfolded and in oper- 105 ative position, the legs are firmly held against displacement or separation and the collapsible corner braces hold each pair of legs rigidly in the same plane, the hooks of course supporting the hammock or swing, not shown.

When it is desired to fold up or collapse the frame, the leg connections 31, 32 are broken or disconnected and the bars 28 are swung up against the legs 24 whereupon the braces 35, 37 are broken or bent permitting the legs and their bars 28 to be folded against the main bar 21.

Inasmuch as these braces 35, 37 are hinged or pivoted to the inner faces of the horizontal top bar and to the corresponding faces of the legs, in the collapsed or folded condition of the structure, they are received inside of the bar 21 as will be readily understood, while the other elements are positioned in close relation to the same bar.

Those acquainted with this art will readily understand the advantages accruing from the employment of a construction of this kind and will comprehend that the invention is not limited and restricted to the precise and exact details of structure, since these may be modified within comparatively wide limits without departure from the heart and essence of the invention as defined in the appended claims.

Stated somewhat otherwise, the invention is susceptible of a variety of embodiments differing more or less in mechanical structure but all incorporating the fundamental principles of the invention.

I claim:

1. In a frame of the character described, the combination of a top angle-bar disposed substantially horizontally with its flanges sloping downwardly in opposite directions, said flanges at points remote from their ends being deflected inwardly and disposed at an

angle to one another of less than ninety degrees, a bracket secured to each end of said top angle-bar and each having a pair of downwardly-projecting ears substantially parallel to the inwardly offset sections of said top angle-bar, supporting legs pivoted to said ears, and foldable braces each pivoted at one end to one of said legs and at its 45 opposite end to the corresponding inwardly offset section of the angle-bar flange.

2. In a frame of the character described, the combination of a top angle-bar disposed substantially horizontally with its 50 flanges sloping downwardly in opposite directions, and with portions thereof remote from its ends deflected inwardly and positioned at an angle to one another of less than ninety degrees, a bracket at each end of said bar bearing against the under faces of and riveted to the flanges of said angle-bar, each bracket having a pair of downwardly-projecting ears substantially parallel to the inwardly offset sections of said 60 angle-bar flanges, angle-bar legs each having the upper end of one flange overlying and pivoted to one of said ears, and collapsible braces connecting each of said legs to said top angle-bar, each brace comprising 65 a pair of bars hinged together, one bar being pivoted to the same flange of the leg as is pivoted to the ear, the companion bar being pivoted to the corresponding inwardly offset section of the flange of said top 70 angle-bar.

In witness whereof I have hereunto set my hand and seal.

JOHN J. O'CONNOR. [L.S.]
